J. B. MASERANG

RAILWAY TIE AND RAIL FASTENER

Filed Oct. 17, 1923

Inventor
John B. Maserang

By *Grace C. Maserang*
Attorney

UNITED STATES PATENT OFFICE.

JOHN B. MASERANG, OF BELLEVILLE, ILLINOIS.

RAILWAY TIE AND RAIL FASTENER.

Application filed October 17, 1923. Serial No. 669,121.

To all whom it may concern:

Be it known that I, JOHN B. MASERANG, a citizen of the United States, residing at Belleville, in the county of Saint Clair, State of Illinois, have invented certain new and useful Improvements in Railway Ties and Rail Fasteners; and I do hereby declare the following to be a full, clear, and exact description of the invention, such as will enable others skilled in the art to which it appertains to make and use the same.

This invention relates to new and useful improvements in railway devices, and particularly to railway ties and rail fasteners.

One object of the invention is to provide a railway tie which is strong and durable, and will permit ready escape of water and mud, from the interior thereof.

Another object is to provide a railway tie of this character which has novel and efficient means for securing the rails thereto, which includes a locking device for preventing retrograde movement of the fastening means.

Other objects and advantages will be apparent from the following description when taken in connection with the accompanying drawing.

In the drawing:

Figure 1 is a side elevation of a railway tie, made in accordance with the invention, partly broken away, and partly in section.

Figure 2 is a vertical transverse sectional view on the line 2—2 of Figure 1.

Figure 3 is an enlarged vertical longitudinal sectional view on the line 3—3 of Figure 2.

Figure 4 is a fragmentary top plan view of the rail and one of the bolts being removed.

Referring particularly to the accompanying drawing, the tie is formed similarly to an elongated metal box 10, having its opposite ends beveled, at 11, and provided with outlet

openings 12 and 13, to permit water, mud, and the like, to escape from the interior of the tie. Extending transversely of the interior of each end of the tie is a vertical wall 14, the lower end of which is provided

with openings to permit water, which might accumulate at the center of the tie, to escape to the ends, and out of the openings 12 and 13. In the upper wall of the tie, and at each side of the space which is occu-

pied by the base of a rail 15, there is formed a thickened portion 16, through which is formed a threaded opening 16' for reception of the rail holding screw 17, to which reference will be made later herein, to a more specific degree. On the upper face 60 of the tie, and surrounding each of the openings 16' is an upstanding flange 18, one side of which is cut away, as shown at 18', to permit the edge of the flange of the rail to lie thereagainst. Projecting from one 65 side of this flange 18 is a lug 19, with which is arranged to engage a portion of the periphery of the flange 20, which is formed on the screw 17, beneath the head. This portion of the flange 20 is adapted to be 70 bent down by the blow of a hammer, so that said portion will lie behind the said lug, and thereby prevent retrograde rotation of the screw in the hole 16', after having been properly screwed home. It will be 75 noted that the diameter of the flange 20 is sufficient to permit a portion thereof to overlie the base flange of the rail, and thereby hold the rail firmly to the tie.

It will be noted that the peripheral edge 80 of the flange 20 is formed with a plurality of radial cuts 21, so that the portion of the flange, at either side of the cut, may be bent down, to engage with the lug 19, or may be 85 engaged with the edge of the base flange 20 of the rail, in the event that such cut does not reach the lug, when the screw is driven home into rail holding position.

Extending longitudinally on the bottom face of the tie is a rib or web 22, which 90 serves to prevent movement of the tie laterally, toward or away from the adjacent ties.

The flange 20 is shown as concavo-convex, whereby to more properly embrace the 95 flange 18.

What is claimed is:

1. A railway tie comprising a body having spaced threaded openings between which to receive the base flanges of rails, a flange surrounding each opening and rising above the face of the top wall, and a screw engaged in each opening and having a bendable flange arranged to overlie the flange of the rail and to engage in locking relation with the said opening flange. 100

2. A railway tie comprising a body having threaded openings spaced in pairs to 105

lie on opposite sides of the base flanges of a pair of rails, a mutilated flange on the upper wall of the body and surrounding the said threaded opening, the mutilated side 5 of the surrounding flange lying against the flange of the rail, a lateral lug on said surrounding flange, and a screw engaged in the threaded opening and having a flange

arranged for engagement with the rail flange and with the said lug.

In testimony whereof, I have affixed my signature, in the presence of two witnesses.

JOHN B. MASERANG.
